ELECTRICAL HIGH-VACUUM DISCHARGE
TUBETheodor Zimmer and Eckhard Fenner,
Erlangen, Germany

Application July 23, 1951, Serial No. 238,114

Claims priority, application Germany
August 19, 1950

10 Claims. (Cl. 313—149)

1
This invention is concerned with an electrical high-vacuum discharge tube having at least one large electrode which is secured to the tube envelope, especially the anode of a rotary anode X-ray tube, and has particularly to do with the mounting or securing of such an electrode.

A drawback arises in the manufacture of such tubes, due to the fact that the electrode, which is prior to the assembly in the tube cleaned and degassed by heating in a vacuum or in a neutral gas, is again heated incident to fusing it to the glass envelope of the tube. The electrode oxidizes incident to this reheating and again takes up gases from the air. These gases escape from the metallic parts in the presence of the high temperatures occurring during the operation of the tube, and therefore have a detrimental effect on the vacuum thereof.

The invention avoids these drawbacks by the provision of a preferably pot-shaped securing or mounting member which is fused to the tube envelope and to which the metallic electrode can be fastened by screw, clamp or bayonet joint means or the like without necessitating heating thereof.

The potlike member may be made of metal and seals one end of the tubular glass wall of the envelope. It can thus easily be cleaned and again degassed after fusing to the envelope glass wall. An auxiliary glass cylinder may be introduced into the corresponding tubular glass extension of the tube envelope during such repeated degassing of the potlike member, for catching and conducting to the outside the liberated gases, thereby avoiding detrimental effects on the inner wall of the glass extension. The metallic electrode (rotary anode), which has been separately degassed, can then be directly fastened, without heating, to the potlike member which has been fused to the envelope extension.

Tubes made in accordance with the invention, as indicated above, secure to a very high degree the maintenance of the high vacuum during the operation thereof.

The objects noted above and other objects and features will appear more clearly from the description which is rendered below with reference to the accompanying drawings. In these drawings,

Fig. 1 shows in diagrammatic, partly elevational and partly sectional representation an example of a rotary anode X-ray tube embodying the features of the invention; and

Fig. 2 illustrates in similar representation another example of the invention.

2
The stator of the rotary anode system has been omitted from the drawings in order to keep them simple.

Referring now to the drawings, numeral 1 indicates in both embodiments the cathode system which may be suitably secured to the re-entrant envelope portion 2. The rotor of the rotary anode system comprises the copper cylinder 3 from which extends the pin 4 carrying the anode disk 5. The copper cylinder is, by means of the iron cylinder 6 (Fig. 1), supported on the journal (not shown) of the rotor carrier. In Fig. 1 this rotor carrier is the metal tube 7, and in Fig. 2 it is the metallic member 13 having a boltlike threaded extension 14 and a flange 18.

The rotor carrier 7 is in Fig. 1 secured in the potlike metallic mounting or securing member 9, and in Fig. 2 it is secured in the potlike member 15. These potlike members are in each case in vacuumtight manner connected with the anode extension 12 of the glass envelope by means of the metallic ring 11 which is fused to the envelope extension wall.

In the embodiment shown in Fig. 1, the rotor carrier 7 is fastened or clamped in the metallic pot 9 by the annular groove 8 formed by the pot wall portion 10. In the embodiment shown in Fig. 2, there is provided on the rotor carrier 13 the threaded boltlike extension 14 which is in threaded engagement with the inside of the metallic pot 15.

The rotor and rotor carrier form in both embodiments a unit which is, prior to mounting in the tube, cleaned and degassed and is then mechanically secured in position without heating, by attachment to the corresponding potlike securing and sealing member which is fused to the envelope wall of the tube, as described.

The copper cylinder 3 of the structure shown in Fig. 2 is provided with a bore 17 through which a suitable key tool is inserted incident to screwing the rotor carrier 13 into the pot 15, the key engaging a bore or depression in the carrier 13, whereby the rotor is temporarily coupled with its carrier so that the screwing of the extension 14 into the pot 15 can be accomplished by rotation of the rotor. The rotor carrier 13 is in mounted position secured against angular displacement, by means of the stud screw 16 which engages the carrier flange 18. The screw 16 is accessible through the pump extension 19.

Mechanical clamping engagement of the tubular rotor carrier 7 with the potlike sealing and securing member 9 (Fig. 1) and threaded engagement of the boltlike extension 14 of the

rotor carrier 13 with the potlike sealing and securing member 15 (Fig. 2) have been shown and described to give examples. It is understood that other equivalent means may be employed such, for example, as bayonet joint means or the like, to accomplish the corresponding connection.

Changes may be made within the scope and spirit of the appended claims.

We claim:

1. Electrical high-vacuum discharge tube having an envelope and a rotary electrode forming a unit including a rotor and a carrier for said rotor, and a device for disposing said electrode unit in said tube, said device comprising a mounting member extending from said carrier, a potlike receiving member which is bonded to said envelope at one end thereof prior to disposing said electrode unit therein, said potlike receiving member forming part of the envelope wall at the corresponding end thereof and forming a recess for receiving said mounting member, and means for mechanically fixedly securing said mounting member in its position in said potlike receiving member.

2. The structure as set forth in claim 1, wherein in said last-named means comprises a thread carried by said mounting member for threaded engagement with said recess in said potlike receiving member.

3. The structure as set forth in claim 1, wherein in said last-named means comprises an annular groove in said mounting member for clamping engagement with a corresponding groove in said potlike receiving member.

4. The structure as set forth in claim 1, wherein in said mounting member is a tubular member for insertion into the recess in said potlike receiving member.

5. The structure as set forth in claim 1, wherein in said mounting member is a threaded boltlike member for threaded engagement with the recess in said potlike receiving member.

6. The structure as set forth in claim 1, wherein in said potlike receiving member is a metallic member carrying an annular radially extending flange, said flange being bonded to said envelope.

7. The structure as set forth in claim 1, com-

prising a first radial flange extending from said mounting member, a second radial flange extending from said potlike receiving member for abutment with said first flange, and means for securing said flange in relatively fixed engagement to prevent angular displacement of said mounting member relative to said potlike receiving member.

8. The structure as set forth in claim 1, wherein in said mounting member is a threaded boltlike element extending axially from said rotor carrier for threaded engagement with the recess in said potlike receiving member, an aperture being formed in said rotor for projecting a tool there-through, during the assembly of said mounting member with said potlike receiving member, for engagement with a recess formed in said mounting member, to facilitate threading of said bolt-like mounting member into said potlike receiving member.

9. The structure as set forth in claim 1, wherein in said potlike receiving member is a tubular metallic member bonded to the envelope of said tube at the corresponding end thereof and extending axially therefrom, a tubular extension projecting from said carrier axially thereof constituting said mounting member, said extension being received in said potlike receiving member and being fastened therein in clamping engagement therewith.

10. The structure as set forth in claim 9, wherein said tubular extension forming said mounting member is fastened in said receiving member by annularly inwardly constricting the wall of said receiving member for engagement with an annular groove formed in the wall of said tubular mounting member.

THEODOR ZIMMER.
ECKHARD FENNER.
